US0D1002285S

(12) **United States Design Patent** (10) **Patent No.:** **US D1,002,285 S**
(45) **Date of Patent:** **** Oct. 24, 2023**

(54) **CONTAINER**

(71) Applicant: **Michael Hoerauf Maschinenfabrik GmbH und Co. KG**, Donzdorf (DE)

(72) Inventor: **Andreas Timar**, Geislingen (DE)

(73) Assignee: **Michael Hoerauf Maschinenfabrik GmbH und Co. KG**, Donzdorf (DE)

(**) Term: **15 Years**

(21) Appl. No.: **29/709,750**

(22) Filed: **Oct. 17, 2019**

(30) **Foreign Application Priority Data**

Apr. 18, 2019 (DE) 402019000360.2

(51) **LOC (14) Cl.** **07-09**

(52) **U.S. Cl.**

(57) **CLAIM**

The ornamental design for a container, as shown and described.

DESCRIPTION

FIG. 1 is a perspective view of a container according to the design;

FIG. 2 is a front view thereof;

FIG. 3 is a side view thereof;

FIG. 4 is a top view thereof; and,

FIG. 5 is a bottom view thereof.

The broken lines define the bounds of the claimed design and form no part thereof.

1 Claim, 5 Drawing Sheets
